(57) **CLAIM**

The ornamental design for a sloped vehicle hood, as shown and described.

DESCRIPTION

FIG. 1 is a front, right top perspective view of a sloped vehicle hood showing our new design;

FIG. 2 is a right elevation view thereof;

FIG. 3 is a left elevation view thereof;

FIG. 4 is a top plan view thereof;

FIG. 5 is a front elevation view thereof; and,

FIG. 6 is a rear elevation view, taken along lines 6—6 of FIG. 2 thereof.

The broken line showing of the vehicle is for illustrative purposes only and forms no part of the claimed design.
